Primary Examiner — T. Chase Nelson*Assistant Examiner* — Kathleen M Sims*(74) Attorney, Agent, or Firm* — Dority & Manning, P.A.(57) **CLAIM**

The ornamental design for a top for an appliance, as shown and described.

DESCRIPTION

FIG. 1 is a perspective view of a top for an appliance showing our new design.

FIG. 2 is a front view of a top for an appliance.

FIG. 3 is a side view of a top for an appliance.

FIG. 4 is another side view of a top for an appliance; and, FIG. 5 is a top view of a top for an appliance.

In the drawings, the cabinet for a dryer in FIGS. 1 through 5 are shown in dashed lines to depict environmental structure and form no part of the claimed design.
